UNITED STATES PATENT OFFICE.

HERBERT L. THOMPSON, OF ELGIN, ILLINOIS, ASSIGNOR TO ELGIN GAS MOTOR COMPANY, OF ELGIN, ILLINOIS, A CORPORATION OF ILLINOIS.

GAS-ENGINE STARTER.

1,300,049.

Specification of Letters Patent.

Patented Apr. 8, 1919.

Application filed May 10, 1918. Serial No. 233,792.

To all whom it may concern:

Be it known that I, HERBERT L. THOMPSON, a citizen of the United States, residing at Elgin, in the county of McHenry and State of Illinois, have invented certain new and useful Improvements in Gas-Engine Starters, of which the following is a specification.

This invention relates to a starter for gas engines of the stationary type which are affixed to the floor, or some suitable support, and is particularly designed and intended to be actuated by the foot of an operator, although of course it may be actuated by hand.

The invention consists in the novel construction, combination and arrangement of parts.

In the accompanying drawings—

20 Figure 1 is an elevation of a starter constructed in accordance with the principles of the invention and applied at one end of a small inclosed gas engine.

Fig. 2 is a sectional detail of the starter 25 engaging pawl.

Fig. 3 is a side elevation of the starter; and

Fig. 4 is a view of the starter showing the parts in actuated position.

30 The present invention is shown as applied to a small gas engine of which the fly wheel is inclosed by a casing 1 and with a driving shaft 2, upon which is keyed a pinion 3. This pinion meshes with a gear 4 which is 35 mounted on a counter-shaft 5, supported in a boss 6 extending from the lower portion of the casing 1, and at the outer end of the counter-shaft 5 is a driving pulley 7, by means of which the engine may be connected to the devices which it operates. Extending over the pinion 3 and the gear 4 is a guard 8 which is supported from the casing 1 by means of ears 9 and fastening screws 10.

45 The inside of the rim of the gear 4 is formed with internal teeth 11, and freely mounted upon the counter-shaft 5, between the gear and the casing, is a ratcheting member 12 having a recess 13, in which a pawl 14 is pressed outwardly for engagement with the teeth 11 by springs 15. This member 12 is also formed with teeth 16 which are arranged at successively different and increasing distances from the axis of the shaft upon which it is mounted, thereby coöperating

55 with teeth 17 of a gear segment 18 pivoted on a projection or stud 19 which extends from the casing 1 below the counter-shaft 5. Secured to, or formed integral with the segment 18 is an operating arm 20, at the extremity of which is a pedal portion 21 which 60 is adapted to be pressed by the foot, or if desired, by the hand of an operator for actuating the gear segment. Attached to one end of the casing 1, and at the other end of the gear segment 18 is a spring 22 which tends 65 to draw the arm 20 in the direction of the counter-shaft 5 in which position the arm 20 engages the spring-pressed pawl 14 and moves it inwardly in the recess 13 against the tension of the springs 15 and out of engagement with the teeth 11 of gear 4. This 70 entirely disengages the pawl 14 from the teeth 11 so that when the engine is in operation there is no connection between the starting members and the ordinary operating and 75 driving parts of the engine. It will be observed that the outer end of the pawl 14 is beveled so that the rotation of the gear 4 in the operating direction will cause the pawl 14 to be simply reciprocated in its recess 13 80 as long as the arm 20 is depressed in the position shown in Fig. 4. Of course, as soon as the arm 20 is released, the spring 22 will draw it upwardly in the position shown in Fig. 1, whereupon the pawl 14 will be disengaged from the teeth 11.

It will be observed in starting this engine that the greatest effort will be exerted at the beginning of the movement of the arm 20 for the teeth 17 of the segment 18 which are 90 nearest to the arm 20 are at the shortest distance from the axis of the stud 19, and therefore the greatest leverage will be exerted upon the ratcheting member 12 as the teeth 16 of this member which are normally in 95 engagement with the teeth of the segment 18 are at the greatest distance from the axis of the shaft 5, and as the arm 20 is rotated to effect the starting movement, the ratio of the distances of the two sets of teeth from their centers increases in the case of the segment 18 and decreases in the case of the ratcheting member 12 so that an accelerated speed is given to the gear 4 with the same speed of movement of the arm 20. It will be 100 observed furthermore that the diameters of the gear 4 and the pinion 3 are in the ratio of about "three to one" so that a complete 105

rotation of the engine 2 is possible with a much less rotation of the gear 4 and of the segment 18.

With this construction there is no danger 5 of a "kick-back" and the gears are fully protected so that there is no danger of their engagement with the clothes or person of an operator, thus making it a particularly desirable starter for women and children to 10 use, with the further advantage that it can be operated by foot, rather than by hand. There are few moving parts which are unlikely to get out of order because they are only used at the time of starting and have no 15 further connection nor interference with the operation.

I claim:—

1. In a gas engine starter, a gear, a rotatable ratcheting member connectible with 20 the gear and having teeth which vary successively in their distance from the axis of rotation, and an operating member having teeth which engage the teeth of the ratcheting member for rotating it.

25. 2. In a gas engine starter, a pair of rotatable members having teeth which vary successively in their distances from the axes upon which they rotate, the teeth meshing with each other, the distances of the successive teeth of one member increasing from 30 its axis as the distances of the other teeth of the other member decrease from its axis.

3. The combination with a gas engine having a driving shaft and a pinion thereon, 35 a counter-shaft having a gear thereon continuously meshing with the pinion and with internal teeth at the rim thereof, and a starter comprising a ratcheting member rotatable on the counter-shaft and having a 40 pawl engageable with the internal teeth of the gear and an operating member for controlling the engagement of the pawl and for rotating the ratcheting member.

4. The combination with a gas engine 45 having an operating shaft and a pinion thereon, of a counter-shaft with a gear thereon continuously meshing with the pinion, a starting member engageable with the gear, and means normally preventing the 50 engagement of the starting member with the gear but operative to rotate and to cause the engagement of the starting member with the gear in a direction to start the engine.

5. In a gas engine starter, a gear rotatable continuously with the engine and having internal peripheral teeth, a ratchet-

ing member rotatable upon the same axis and having a pawl engageable with the internal teeth of the gear, and means for rotating the ratcheting member including an 60 arm which normally engages the pawl for holding it out of engagement with the teeth.

6. In a gas engine starter, a rotatable member, a ratcheting member having a 65 spring-pressed pawl engageable with the rotating member, and means for rotating the ratcheting member including an arm for engaging the pawl and a spring for normally drawing the arm into engagement 70 with the pawl and pressing it out of engagement with the rotatable member.

7. The combination with a gas engine, of a foot starter therefor comprising a pair of convolute gears meshing with each other 75 and one of them having an arm attached thereto for exerting greater leverage upon the other at the beginning of the starting movement, and means for returning the gears to the same starting position. 80

8. In a gas engine starter, a rotatable gear having internal teeth, a ratcheting member having a spring-pressed pawl for engaging the teeth, the ratcheting member having teeth which successively differ in distance 85 from its axis of rotation, a pivoted gear segment meshing with the teeth of the ratcheting device, and an arm connected with the segment for imparting an accelerating movement to the ratcheting member for the 90 same continuous movement of the arm.

9. In a gas engine starter, a rotatable member, a ratcheting device connectible with the member, and operating means having a convolute geared connection with the 95 device for producing an accelerating movement on the device for the same continuous movement of the operating means.

10. In a gas engine starter, a rotatable gear, a ratcheting member having a common axis and engageable with the gear to rotate it in one direction, a pivoted segment having an operating arm, and a convolute geared connection between the segment and the member by which an increased starting 100 pressure is exerted upon the member than after it is started for the same application of pressure to the arm. 105

In testimony whereof I have signed my name to this specification on this 6th day of 110 May, A. D. 1918.

HERBERT L. THOMPSON.
